UNITED STATES PATENT OFFICE.

NEWMAN H. HOLLAND, OF MONTCLAIR, NEW JERSEY; CHARLOTTE MARY HOLLAND
ADMINISTRATRIX OF SAID NEWMAN H. HOLLAND, DECEASED.

PHONOGRAPH NEEDLE.

Application filed July 21, 1926. Serial No. 123,849.

The needles which are ordinarily used with phonographs come within two general classes—those which taper gradually and terminate in a point which is of the proper size for engagement in the groove of a sound record, and those which are tipped with a fine wire which is of uniform cross section and presents a point which is of the proper size regardless of the extent to which worn. 5 The tapering needles are quite inexpensive to manufacture, but are objectionable in that the points wear away rapidly in use and necessitate the employment of a new needle for each record played. The wire tipped 10 needles, while a little more expensive to manufacture, give much better results and can be used over and over again if the wires are sufficiently long and do not become bent.

Heretofore it has not been feasible to extend the wire of a wire tipped needle more than a few thousandths of an inch beyond the end of the wire holder, as otherwise the wire would bend, and, when the wire is short enough to withstand bending, it cannot be 25 used many times before being completely worn away.

The principal object of this invention is to provide a wire tipped needle having a relatively long wire which will not bend in 30 ordinary usage.

Another object of the invention is to provide an improved needle of the character described which is capable of eliminating in large measure the surface noises emanating 35 from the record.

Other objects and advantages will be evident to those skilled in the art upon a full understanding of the construction of the improved needle.

In order that the invention may be readily understood, one embodiment of the same, together with two slight modifications, is herein illustrated and described, but it will be understood, of course, that the invention is 40 susceptible of embodiment in various other forms coming equally within the comprehensive scope of the claims.

In the accompanying drawing,

Fig. 1 is a side view of a phonograph needle constructed in accordance with the invention;

Fig. 2 is a longitudinal section, taken on the line 2—2 of Fig. 1;

Fig. 3 is an end view of the needle;

Fig. 4 is a transverse section taken on the 55 line 4—4 of Fig. 2;

Fig. 5 is a side view of the needle as it would appear in use;

Fig. 6 is an end view of a slightly modified form of the needle; and

Fig. 7 is an end view of another slightly modified form.

The needle which is illustrated in Figs. 1 to 5 inclusive of the drawing consists of a holder 10, a fine wire 11 which extends from 65 one end of the holder in axial alignment with the same, and a coating 12 of a material on the wire which is readily wearable with respect to the sound record with which the wire is adapted to coat. The holder 10 70 is an elongated brass tube of circular cross section, and the wire 11, which is also of circular cross section, extends through the holder and is in fixed frictional engagement therein. The coating 12 is molded about the 75 wire 11 between the end of the holder and the tip of the wire, and may be of any readily wearable material which will afford sufficient reinforcement for the otherwise unsupported portion of the wire extending beyond the end of the holder. One suitable 80 composition for the coating consists of beeswax, resin and graphite, in the proportions of 25% beeswax, 25% resin and 50% graphite.

The needle is used like any ordinary needle. The holder 10 is inserted within the needle-engaging socket 13 of a sound box 14, and is held fixedly therein by means of a set screw 15. The point of the needle is placed 85 upon the grooved portion of the rotating record, and immediately conforms to the groove in the record, the coating 12 wearing away flush with the upper edge of the grooves in the record and leaving an extremely short 90 portion 16 of the wire exposed for engagement within the groove. The lower end of the wire will wear away slowly in use, and, as it does so, the remaining portion of the wire continues to be supported by the coating 12, which coating wears away at a corresponding rate in a shifting plane located just 95 above the point of the wire, as clearly shown in Fig. 5.

By the employment of the coating 12, the 105 wire 11 is reinforced throughout practically the entire length thereof beyond the end of the holder 10, and the portion of the coating

which comes into contact with the grooved surface of the record acts to lubricate the latter and eliminate in large measure the surface noises which would otherwise emanate therefrom.

In Figs. 6 and 7 are shown two slightly modified forms of the needle. They differ from the form shown in Figs. 1 to 5 inclusive only in the respect that in Fig. 6 the 10 wire 17 is shown as of rectangular cross section, and in Fig. 7 the wire 18 is shown as of diamond-shape cross section. The purpose of shaping the wire in such fashion is to obtain an edge which is as narrow as possible 15 in one direction, so that the point of the needle, will readily fit into the high frequency waves in the grooves of the record. Instead of being of rectangular or diamond shape, the wire might be of oval, triangular, or other 20 form. When a wire is used which is other than of circular form, the holder may advantageously be made flat at a point on one side thereof in order to prevent the same from turning when engaged by the positioning screw of the sound box.

The particular shape of the holder for the wire is immaterial, and the holder need not be a separate member, but may be formed integral with the wire, the wire in such case 30 being a reduced extension of the holder or shank portion.

I claim:

1. A phonograph needle, comprising a 35 holder, a fine wire secured to and extending from the holder for coaction with a sound record, and a coating of a material on the wire which is readily wearable with respect to the sound record.

2. A phonograph needle, comprising an 40 elongated holder, a fine wire secured to and extending from one end of the holder in axial alinement therewith for coaction with a sound record, and a coating of a material on the wire which is readily wearable with respect to the sound record.

3. A phonograph needle comprising a 45 holder, a fine wire secured to and extending from the holder for coaction with a sound record, and a coating of a material on the

wire which is readily wearable with respect 50 to the sound record, said coating containing beeswax.

4. A phonograph needle, comprising a 55 holder, a fine wire secured to and extending from the holder for coaction with a sound record, and a coating of a material on the wire which is readily wearable with respect to the sound record, said coating containing resin.

5. A phonograph needle, comprising a 60 holder, a fine wire secured to and extending from the holder for coaction with a sound record, and a coating of a material on the wire which is readily wearable with respect to the sound record, said coating containing 65 graphite.

6. A phonograph needle, comprising a 70 holder, a fine wire secured to and extending from the holder for coaction with a sound record, and a coating of a material on the wire which is readily wearable with respect to the sound record, said coating containing beeswax, resin and graphite.

7. A phonograph needle, comprising a 75 holder, a fine wire secured to and extending from the holder for coaction with a sound record, and a coating of a material on the wire which is readily wearable with respect to the sound record, said coating containing beeswax, resin and graphite in the approximate 80 proportions of 25% beeswax, 25% resin, and 50% graphite.

8. A phonograph needle, comprising a shank which is provided at one end with a reduced extension for engagement within a 85 record groove, and a heavy coating of a material in intimate contact with the reduced extension, which material is readily wearable with respect to the record.

9. A phonograph needle, comprising a fine 90 wire for engagement within a record groove, and a heavy coating of a reinforcing material about the wire, which material is readily wearable with respect to the record.

In testimony whereof I have hereunto sub- 95 scribed my name.

NEWMAN H. HOLLAND.
